UNITED STATES PATENT OFFICE.

OTIS L. BEARDSLEY, OF CHICAGO, ILLINOIS.

SLED.

No. 907,217.

Specification of Letters Patent.

Patented Dec. 22, 1908.

Application filed September 16, 1908. Serial No. 453,219.

To all whom it may concern:

Be it known that I, OTIS L. BEARDSLEY, citizen of the United States, residing at Chicago, in the county of Cook and State of Illinois, have invented a certain new and useful Improvement in Sleds, of which the following is a full, clear, concise, and exact description.

My invention relates to a sled and more particularly to a sled in which the runners are adapted to be folded when not in use. Its object is to provide a sled of simple construction which is strong and which may be readily folded or secured in the open or running position.

My invention consists of a sled provided with a pair of runners formed of a metal rod bent in the shape of an elongated loop, the ends of which are pivoted to the body of the sled in order that they may be readily folded or opened, and a folding U-shaped brace pivoted beneath the body of the sled and adapted to bear against the inner side of the loop approximately midway between its ends to brace the same.

One feature of my invention contemplates a brace having such construction that it engages directly with the runners and requires no intermediate fastening means to hold the same in place against said runners.

Another feature of my invention consists in so constructing the brace that when it is in its open position the weight upon the body of the sled has no tendency to cause said brace to collapse.

These and other features of my invention may be more readily understood by reference to the accompanying drawings, in which—

Figure 1 is a side elevation of a sled embodying my invention; Fig. 2 is a bottom plan view thereof with the runners adjusted to their running or open position; Fig. 3 is a bottom plan view showing the parts in their folded position; and Fig. 4 is a fragmentary bottom plan view showing a modified form of bracing member.

Like parts are designated by similar reference characters throughout the several views.

The runners 1, 1 each consist of a rod, preferably of metal such as steel, bent into the form of an elongated open loop, each end of the loop being pivoted to the body 4 of the sled and preferably beneath the same. Such pivotal connection may be provided by bars 2 which extend transversely across the bot-

tom of the sled at each end thereof and in which sockets are formed near the edges of the sled in which the ends of the rods 1, 1 are pivoted. Each end of the rod 1 is bent outwardly as at 3 at approximately right angles to the plane of the runners. When said runners are thus in their open position the angular projections 3 lie against the bottom of the sled body 4 and limit the outward movement of the runners 1.

In order that there may be no tendency of the runners folding together when the sled is in use, I preferably have those portions of the runners which engage with the ice or snow over which the sled is drawn slightly outside of the vertical plane passing through the pivotal points of said runner. This feature is shown in somewhat exaggerated form for the sake of clearness in Fig. 2. With such construction, however heavy the weight placed upon the body of the sled, there is no tendency of the runners to collapse inwardly into a folding position. Pivoted beneath the body 4 is a U-shaped brace. Said brace consists of a base 5 and two arms 6, 6, the base 5 extending transversely of the sled at a point intermediate its ends, and is pivotally secured beneath the body 4 in suitable bearings 7, 7. The U-shaped brace, when the runners are in their folded position, may be folded against the bottom of the sled as shown in Figs. 3 and 4.

The base 6 of the U-shaped bracket is provided with one or more bends 8, said bends being formed at an angle slightly less than 90° with respect to the arms 6, 6 of the brace. Said bends 8 are adapted when the brace is in its open position to lie against the bottom of the body 4 of the sled and thus limit the open position of the brace. As shown in Fig. 3 the arms 6 fold toward the front of the sled, and when said brace is in engagement with the runners 1, the arms 6 extend downwardly and to a slight extent backwardly. In short, the arms 6 in their open position lie slightly back of a plane extending through their pivotal axis. It will thus be seen that any strain or weight placed upon the sled will have no tendency whatever to cause said brace to collapse into its folded position.

The free ends of the arms 6, 6 are preferably provided with grooves 9, 9 for receiving the runners 1, 1. Said runners 1 are also preferably slightly bowed inwardly when not in engagement by the brace, as shown in

Fig. 3. However, when said runners are engaged by the brace, they are sprung outwardly so as to form a horizontal straight line, as shown in Fig. 1, the runners 1 thus 5 themselves exerting a spring pressure upon the **U**-shaped brace, thus increasing the frictional engagement of said brace and runners and decreasing any tendency to collapse.

10 The bends 8, 8 and the base 5 may be so spaced apart that when the brace and the runners are in their folded position said runners are sprung into the opening between the bends 8, 8 and thus locked in a folded position, as shown in Fig. 4.

15 While I have shown my invention as embodied in a hand sled, it will be understood that said invention may also be embodied in sleds of a larger structure, and of varying types.

20 I claim:

1. In a sled, the combination with a body, of a pair of folding runners each consisting of a rod in the form of an elongated loop having its ends pivoted to said body, and a 25 **U**-shaped folding brace pivoted at its base upon the under side of said body transversely thereof, the ends of the two arms of said **U**-shaped brace being each provided with a groove for receiving the corresponding runner when the parts are in their open 30 position.

2. In a sled, the combination with a body, of a pair of folding runners each consisting of a rod in the form of an elongated loop

having its ends pivoted to said body, and a 35 **U**-shaped folding brace pivoted at its base upon the under side of said body transversely thereof, said base being provided with one or more bends extending at an angle slightly less than 90° with respect to the plane of the 40 arms of the brace, said bends engaging the under side of said body and the ends of the arms of said **U**-shaped brace engaging with said runners when the sled is unfolded for use.

45 3. In a sled, the combination with a body, of a pair of folding runners each consisting of a rod in the form of an elongated loop having its ends pivoted to said body, the central portion of each runner being slightly 50 bowed inwardly with respect to the loop when the runner is folded, and a **U**-shaped folding brace pivoted at its base upon the under side of said body, transversely thereof, the ends of the two arms of said **U**-shaped 55 brace being each provided with a groove for receiving the corresponding runner when the parts are in their open position, the arms bearing against said runners and pressing said bowed portions thereof into approximately straight lines.

In witness whereof, I hereunto subscribe my name this 8th day of September A. D., 1908.

OTIS L. BEARDSLEY.
